[57] ABSTRACT

There is disclosed an interfacing system for driving row-column conductor arrays to the gas discharge display panel in a low cost integrated circuit assembly. Due to the requirement of opposite polarity or bidirectional signals being applied to the conductors in the arrays, although the integrated circuits are functionally identical in translating low level logic signals to relatively high voltage (150 volts) pulse signals which are algebraically added to sustainer voltages, one of the circuits includes as a part of the logic circuit an inverting transistor; and to reduce current loading by the logic circuit on external data sources and at the same time serve as a part of a logic gate; and the high voltage switching circuits include a feedback diode for enhancing the response time.

**HIGH VOLTAGE PULSER CIRCUIT FOR DRIVING
ROW-COLUMN CONDUCTOR ARRAYS OF A GAS
DISCHARGE DISPLAY CAPABLE OF BEING MADE
IN INTEGRATED CIRCUIT FORM**

The present invention relates to new and improved circuitry for supplying discharge condition manipulating pulse potentials to the row-column conductor matrices of gas discharge display-memory panels of the type disclosed in Baker et al. U.S. Pat. No. 3,499,167 and British Patent Specification 1,161,832. It is an improvement on the circuits disclosed in Johnson U.S. Pat. application Ser. No. 888,743, now U.S. Pat. No. 3,611,296 and Johnson patent application Ser. No. 821,306, now U.S. Pat. No. 3,614,739. The gas compositions used in the panel shown in the Baker et al. patent have been greatly improved to now permit driving same by integrated circuits. In such gas discharge panels, the applied voltages are usually of two types, one, typically denoted as the sustainer voltage, is a periodic voltage which may be continuously or discontinuously applied but is typically of a sinusoidal, square, triangular, etc., wave shape. This sustainer voltage must be applied commonly to all row and column conductors and, typically, one-half of the sustainer voltage is applied to one of the conductors of the array and the other half, 180° out of phase with respect to the former half, is applied to the other conductors of the array and, as in a preferred arrangement as disclosed in the aforementioned Johnson patent applications, are applied via the pulsing circuits which supply the other potentials referenced above. This second potential is a unidirectional voltage pulse, one-half applied to the row conductors and one-half of which is applied to the column conductors but of opposite polarity. Because of the relatively large numbers of panel lines to be driven, the circuitry for driving a row-column conductor array in the panels must be constructed at relatively low cost and high reliability. At the same time, it is highly desirable to provide logic circuitry in the integrated circuit environment or structure so as to reduce the number of wires or conductors to the panel. In this connection, the logic circuitry pulse as well as the arrangement of the circuits on the panels are known. It will be apparent that the circuitry disclosed herein need not be directly mounted on the panel but may be mounted on printed circuit boards and connected to the panel by flexible cables, conductors and the like.

Referring now to the drawing, which discloses a preferred embodiment of this invention, there is shown a gas discharge display/memory panel of the type disclosed in Baker et al. U.S. Pat. No. 3,499,167.

The panel is composed of a pair of glass plates 10 and 11, plate 10 carrying conductor array 12 and plate 11 carrying column conductor array 13, respectively. The odd numbered conductors in the row conductor array 12 being served from one side of the panel whereas the even numbered conductors may be served from the opposite side (not shown). In a similar fashion, column conductors 13 are carried on plate 11 and odd numbered or alternate ones of the column conductors C1, C3, C5 and C7 etc., are served from the upper plate extension, whereas the even numbered column conductors are served from circuitry on an opposite edge extension of plate 11 (not shown). It will be appreciated that all conductors may be served from the same side or in various other orientations or groupings not here pertinent.

The conductors within the active area of the panel have a dielectric charge storage coatings 15 and 16, respectively, and the plates are joined by a spacer sealant 17 to form a thin (under about 10 mils) gas discharge chamber 18 containing a gaseous discharge medium. The gas may be of a type and in the pressure range disclosed in Belgian U.S. Pat. No. 739,303 corresponding to Nolan application Ser. No. 764,577, filed Oct. 2, 1968.

Each of row conductors, R1, R3, R5, and R7, is served by an individual pulser PR1, PR3, PR5, and PR7, respectively, all of which are on one monolithic semiconductor body, and each of the column conductors C1, C3, C5, and C7, served by an individual column PC1, PC3, PC5, and PC9, respectively, which are on a monolithic semiconductor body of opposite conductivity type. As shown, each pulser is associated with a gate circuit (to be described in greater detail hereinafter) each gate circuit requiring an enable pulse which is applied in common to the gate circuit in all pulsers in a sector on row enable bus 21 and a data input pulse as applied on data input terminals, row data 1, row data 3, row data 5, . . . row data 7. Similarly, the column pulsers PC1, PC3, PC5, and PC7 are each equipped with logic circuitry driven by a pair of input pulses, one of which is the column enable pulse which activates column enable bus 22 and the column data terminals, column data terminal 1, column data terminal 3, column data terminal 5, . . . column data 7. Thus, in order to activate any pulser circuit whether it be a column pulser or a row pulser requires two pulses, one specific to the pulser circuit per se as applied to the "data" terminals and one specific to a particular sector or area of the panel and designated as the enable pulse (row and/or column). It will be appreciated that more or less pulser chips may be controlled by a single enable pulse to row or column pulsers, respectively.

All of the pulser circuits require a low voltage (VLV1, VLV2) (no greater than approximately 12 volts) potential for operating the control or logic circuitry inputs and a relatively higher voltage (VHV1, VHV2) (approximately 150 volts) for supplying high voltage pulses to be algebraically added to the sustainer voltages (of about the same magnitude). This direct current voltage is bidirectional in the sense that there is a corresponding negative voltage (-VHV2) applied in common to all of the row pulser packages and having a common terminal. As shown there are four power supplies (VLV1, VLV2, VHV1, and VHV2). One set (VLV1, VHV1) supplies the column pulsers and one set (VLV2, VHV2) supplies the row pulsers. These two sets are each floating on opposite phases (or sides) of the Sustaining Voltage (VS). It will also be noted that as in the case of the above-referenced Johnson patent applications, the sustainer voltages (Vs/2) are applied in series with the high direct current voltage and passes substantially unattenuated through the pulser circuits to the row and column conductors, respectively.

**HIGH VOLTAGE PULSER CIRCUIT
CONFIGURATIONS**

Referring now to circuit configuration PC-1, switching transistors Q3 and Q4 form a totem pole output stage driven by transistor Q2. Transistor Q1 is used as an active load and resistor R1 supplies current to transistor Q2 which in turn drives on switching

transistor Q4. (Switching transistors Q3 and Q4 correspond to the output switching transistors of the above-referred Johnson patent applications and diode CR4 corresponds to diode D2, resistor R4 corresponds to resistor R3 of said Johnson applications, so the switching action is essentially the same.)

Resistors R1 and R2 are used to split the current and are driven by the gate consisting of data diode CR1 and enable diode CR2. Current splitting is used to determine the amount of current coming out of transistor Q2 which in turn drives on switching transistor Q4. Diode CR3 is a feedback diode, similar in action to the well known Baker clamp, and is used to drive the active load into a reduced conduction condition, to keep the switching transistor out of deep saturation. Output contact area OCA-1, in addition to having the sustainer potential thereat, will be pulsed to +VHV (+175 volts) less the small saturation drop in transistor Q4, and diode CR4 whenever transistor Q3 is rendered non-conductive.

Each data input signal in conjunction with the signal voltage output of the enable circuitry (comprising resistor R5, transistor Q5, resistor R6 and phase inverter transistor Q6), is used in a gating configuration formed by CR1 and CR2 to allow transistor Q2 to turn on which, in turn, turns on switching transistor Q4. The ratio of resistor R1 to resistor R2 determines the current split which thereby reduces the impedance of transistor Q1 in the "on" condition. During the turnoff of transistor Q4, enough stored charge could exist on the base so the recombination time would increase the output turn-off delay. This has been improved by the use of feedback diode CR3 to greatly reduce the number of minority carriers and attendant recombination time. As indicated above, the mechanism is similar to a Baker clamp diode where the collector to base junction of transistor Q4 is prevented from deep saturation by action of feedback CR3. The pulser circuitry for the row conductors, except for the observance of polarity considerations (NPN vs. PNP) is the same.

Enable circuitry for the row pulser circuits differs from that for the column pulser circuits in that on the row pulser circuits a single transistor Q3 is used to transfer the enable signal. The high enable signal may have the same polarity for both pulser circuits (row and column) whereas all other polarities are opposite. For the column pulser circuits the enable signal turns off transistor Q5 which in conjunction with resistor R5 removes the drive current and thus shuts off current amplifier transistor Q6. The output of transistor Q6 controls all enable inputs on the column pulser circuits. This in effect forms a phase inverter which permits the enable input signal to be of the same polarity as the opposite circuit in the row pulser circuits. On the row pulser circuits, diodes CR5 and QE are used in conjunction to form a gate and function in the identical manner as diodes CR1 and CR2 on the column pulser circuits. Transistor QE is used to reduce the amount of current taken from the enable input when it is in the "on" condition. As is known, in a dielectric isolation construction N-type wafers and P-type wafers are permitted, N-type wafers may have lateral PNP-transistors but the reverse is not desirable. This accounts for QE and associated PNP's being used on the row conductor pulser circuit chips and the opposite function not being used on the column conductor pulser circuit chips.

Although the function of the circuits for driving the row and column conductors are identical in converting or translating low level logic signals to high level voltages and at the same time passing, in unaltered form, the sustaining voltage, because of the differences in conductivity types and the inherent differences in materials for fabricating such structures, the circuits are different. It is with respect to the specific high voltage transistor switching circuitry having its response time enhanced by a speed-up diode and an active transistor and in the unique combination of logic input enabling means that the invention is directed. It is with respect to the supplying of such potentials to a gas discharge display/memory panel of the type disclosed in the aforementioned Baker et al. patent as well as other gas discharge panels and cross matrix display systems that the invention finds specific usefulness.

In the disclosed preferred embodiment, four row conductor pulsers and their related input and output terminals, voltage supply terminals and interconnecting conductors (as for example, the "row enable" input contact terminal or area and conductor to each of the row enable transistors QE) are formed on a single chip and in like manner the column pulsers are formed on a single chip. However, in connection with the column enable circuitry, it will be noted that transistors Q5 and Q6 as well as related resistors R5 and R6 are used in common with all column pulsers.

Features of the invention as described above and to which the appended claims are directed include the feedback diode CR3 which is used to enhance the response of the switching transistors; transistor Q1 which functions as an active load on transistor Q2 to provide a high speed drive thereto, transistor Q2 as an active element coupling the logic circuit to the switching transistor circuitry; transistor Q5 used as a drive for phase inverter transistor Q6 to commonly control all diodes CR2 of the gate circuits in the column pulsers, and transistor QE for the transferred logic enabling pulses, which thereby permit the same enabling pulses to be used for both kinds (row and column) of pulser circuits and, finally, resistors R1 and R2 are used to split or divide current the effect being active control of the impedance seen by the collector of transistor Q2.

What is claimed is:

1. In an electrical circuit system for supplying sustaining voltages and discharge manipulating pulse voltages to one group of row conductors and one group of column conductors in a gas discharge panel device to enter and remove information on said panel and in which transversely oriented row and column conductors effecting discharges in the gas have dielectric charge-storage means for charges produced on discharge interposed between said row and column conductors and the gas, at least a pair of monolithic semiconductor bodies, one for each said group of conductors and each processed to include a plurality of individual dielectrically isolated high voltage transistor switching circuits connected by conductors in circuit configurations described hereinafter including a plurality of contact areas to which connections to and from said circuit configurations are made, each said circuit configuration being functionally identical, wherein: each circuit configuration translates a low level input pulse signal voltage to a high level pulse

signal voltage and feeds through a high level periodic signal voltage as said sustaining voltage, and means for supplying a low level input voltage constituting a source of said information to be entered on said panel, the improvements wherein each of said high voltage transistor switching circuit includes diode feedback means between the collector of said high voltage switching transistor and said source of information signals for speeding the response of said switching transistor circuit, a further transistor element for each said circuit configuration, said further transistor element being operatively connected between said means for supplying a low level input voltage and said high voltage transistor switching circuit for each circuit configuration, respectively.

2. The invention defined in claim 1, said means supplying a low level input voltage is constituted by a multiple low voltage pulse signal input gate circuit, and one of said low voltage signal inputs is common to all said circuit configurations in a group for enabling same and wherein a further improvement comprises,

a transistor phase inverter circuit for receiving and inverting the phase of said common low voltage signal input, and

a current amplifier circuit for supplying an inverted current signal to said multiple input gate circuit as said common low voltage signal.

3. The invention defined in claim 1, said means sup-

plying a low level input voltage is constituted by a multiple low voltage pulse signal input gate circuit and one of said low voltage signal inputs is common to all said circuit configurations in a group on a common semiconductor body, for enabling same and wherein a further improvement comprises a transistor phase inverter circuit for inverting said common signal input voltage, there being one phase inverter for each said circuit configuration and each said phase inverter circuit being a part of said gate circuit.

4. The invention defined in claim 3 wherein the semiconductor bodies are of the opposite conductivity types, the further improvement wherein the other circuit configurations on the other of said semiconductor bodies include;

a further transistor phase inverter for receiving and inverting the phase of said common low voltage signal input, and

a current amplifier for supplying an inverted current signal to the multiple input gate circuit of each gate circuit, respectively, on said body as said common low voltage signal, whereby the number of discharge points in said panel enabled by said common enable voltage is the product of the number of said row conductors in a group and the number of column conductors in a group.
